UNITED STATES PATENT OFFICE.

IVORY W. HARLOW, OF PLYMOUTH, MASSACHUSETTS, ASSIGNOR TO THE PLYMOUTH FOUNDRY COMPANY, OF SAME PLACE.

STOVE.

SPECIFICATION forming part of Letters Patent No. 273,730, dated March 18, 1883.

Application filed May 19, 1882. (No model.)

To all whom it may concern:

Be it known that I, IVORY W. HARLOW, of 5 Plymouth, in the county of Plymouth and State of Massachusetts, a citizen of the United States, have invented a certain new and useful Improvement in Stoves, of which the following is a full, clear, and exact description, reference being had to the accompanying drawings, forming a part of this specification, in explaining its nature, in which—

Figure 1 is a perspective view of a stove embracing my invention; and Fig. 2 is vertical section thereof, further illustrating the construction.

15 This invention relates to that class of cooking-stoves having what is known as the "cabinet-base," and it consists in providing the cabinet-base with a hot-closet drawer, which is adapted to be moved out and in horizontally in relation thereto.

Heretofore the portion of the cabinet-base under the central portion of the stove, so far as I am aware, has not been employed for any useful purpose, and by my invention I utilize 25 this space by arranging a hot-closet drawer, adapted to be moved out and in from the base, made of sheet-iron, and an ornamental front plate, which corresponds in ornamentation to the rest of the base. This hot-closet drawer 30 preferably has sheet-metal sides, bottom, and rear end, is open on top, and has the cast-metal front. It is arranged to slide upon ledges or supports extending across the interior of the cabinet-base. The base is of ordinary construction, and it is made of cast-metal sides and ends, and, like all cabinet-bases, it has a skeleton frame not forming a portion of the 35 stove, and simply designed as a stand to elevate the stove to a desirable height.

40 In the drawings, A is the cabinet-base. a are the ledges or supports for the movable hot-closet drawer. B is the hot-closet, having the sheet-metal bottom b, sides b', and inner end, b''. The front of the closet-drawer is the cast-metal plate b, which also forms the front surface of the cabinet-base. A suitable handle or handles may be arranged upon the front plate for moving the hot-closet drawer, if desired. A movable hot-closet of this description 45 not only utilizes the space heretofore wasted, but has an advantage over the stationary

hot-closet used on stoves not provided with cabinet-bases, in that the closet may be drawn out and the article to be warmed or heated placed in and removed therefrom while it is 55 out and while the whole lower surface of the closet is exposed to view—a very great advantage.

It will be observed that the hot-closet drawer herein described differs from an ordinary ash-pan, in that it is not located so as receive 60 ashes, and has no connection with the ash-pit, and in that its front plate, b³, forms a portion of the front or side wall of the cabinet-base.

65 I am aware that the Patent No. 78,890, dated June 16, 1868, granted D. E. Paris, shows and describes a stove having beneath its main oven a separate warming-oven which is supported on rollers, and is adapted to be moved 70 from beneath the stove when desired, and that this separate warming-oven is provided with doors. As, however, said stove is not provided with a cabinet-base having a hot-closet drawer 75 adapted to be moved out to expose its contents, and which is unprovided with doors, I consider that the said patent does not embrace the spirit of my invention.

Having thus fully described my invention, I claim and desire to secure by Letters Patent 80 of the United States—

1. The combination of a cabinet-base, A, with a movable hot-closet, B, all substantially as and for the purposes described.

2. The combination of the cabinet-base A 85 and the ledges or supports a with a hot-closet having for its front the front plate of the cabinet-base, which closet is adapted to be moved out and in relation to the base horizontally, all substantially as and for the purposes described.

3. The combination of a stove with a base portion having a hot-closet, B, the front piece of which furnishes the front of said portion, and which hot-closet is adapted to be moved 95 horizontally in said portion of the stove, all substantially as and for the purposes described.

IVORY W. HARLOW.
